UNITED STATES PATENT OFFICE.

ROLANDIS A. BLAIR, OF FORT WAYNE, INDIANA, ASSIGNOR TO THE P. & M. COMPANY, OF CHICAGO, ILLINOIS, A CORPORATION OF ILLINOIS.

RAIL ANCHOR.

Application filed October 3, 1922, Serial No. 592,047. Renewed June 6, 1923.

To all whom it may concern:

Be it known that I, ROLANDIS A. BLAIR, a citizen of the United States, residing at Fort Wayne, in the county of Allen and State of Indiana, have invented certain new and useful Improvements in Rail Anchors, of which the following is a specification.

My invention relates to devices for preventing the longitudinal creep of railroad rails, these devices being commonly called rail anchors, anti-creepers, or rail stays.

One of the objects of my invention is the provision of a rail anchor of simple and compact construction, inexpensive to manufacture, which will maintain a reliable hold on the rail as against the tendency of the device to become loosened by vibration or other disturbing influences, and which may be quickly and conveniently put in place on the rail, or removed therefrom, if occasion requires.

It is a further object of my invention to provide a rail anchor which can be used with rails, the bases of which are of different width or of different contour.

A further object of my invention is the provision of a rail anchor adapted to prevent the longitudinal creep of railroad rails in both directions.

A further object of my invention is the provision of a rail anchor so constructed that it may be removed and replaced several times without impairing its holding power.

The invention consists in the novel arrangements and constructions to be herein-after described and claimed for carrying out the above stated objects and such other objects as will appear from the following description of a preferred embodiment illustrated in the accompanying drawings, 40 wherein—

Fig. 1 is a plan view of a fragmentary portion of a railroad rail provided with a device embodying the principles of my invention;

Fig. 2 is a side elevational view of the device; and

Fig. 3 is an end elevational view of the device.

Like characters of reference designate like parts in the several views.

Referring now to the drawings, the embodiment therein illustrated is formed from a slightly resilient steel bar 6, rectangular in cross section, which is bent about a vertical axis substantially medially of its length,

the arms or portions 7 and 8 thereof extending substantially parallel with respect to each other and substantially transversely under the rail base 9. The portions 7 and 8 are then bent downwardly, upwardly and outwardly to provide foot pieces 10 and 11, respectively, which are adapted to bear against the side of a tie 12 and also to provide seats or bearings 13 adapted to engage the under side of the rail base flange 9^a. The free ends of the portions 7 and 8 are then bent upwardly and back to form jaws 14 and 15, respectively. The extremities 16 and 17 of the respective jaws are bent in opposite directions substantially at right angles to the jaws so that they extend longitudinally of the rail when the device is applied thereto. The connected ends of the portions 7 and 8 are offset upwardly to provide a shoulder 18 adapted to engage the edge of the base flange 9^b, the device as a whole being substantially in the form of a yoke.

In applying the device to the rail, the jaws 14 and 15 are slipped over the rail base flange 9^a so that the device occupies a position substantially as shown in dotted lines, Fig. 2, with one of the foot pieces in engagement with the side of the tie. The ends of the jaws are then struck with a sledge hammer or the like and the device driven transversely onto the rail base until the shoulder 18 coincides with the edge of the base flange 9^b and that end of the device snaps upwardly with the upper sides of the portions 7 and 8 adjacent their connected ends bearing against the bottom of the base flange 9^b. The jaws, their respective extremities, and the foot pieces, when the device is free of the rail, occupy substantially the position shown in dotted lines in Fig. 3, with the vertically extending portions of the jaws in converging position, and when the device is applied to the rail, the extremities of the jaws are forced to climb the inclined surface of the flange 9^a, thus forcing said extremities away from the plane of the seats 13 and serving to twist the jaws in opposite directions toward parallelism with each other. The two portions of the device extending under the rail base, therefore, are subjected very considerably to opposed twisting strains. The tendency of the device to return to its original shape results in a strong, reliable gripping action on the rail base ample to prevent any slippage of the device longitudinally.

on the rail notwithstanding the disturbing influences to which the device is subjected due to the passage of heavy rolling stock and weather conditions.

5 The jaws 14 and 15 are so formed that a considerable clearance is provided between the inner sides of said jaws and the adjacent edge of the base flange 9^a, also between the under faces of said jaws and the major portion 10 of their extremities and the upper surface of said base flange. The ends of the longitudinally extending portions 16 and 17 are, however, only slightly above the level of the seats or bearings 13, as is shown by 15 dotted lines in Fig. 3, and the tendency of the jaw extremities to remain relatively close to the plane of the seats 13 is great enough to cause the device to have a strong operative grip when applied to rail bases relatively 20 narrow in width as well as to rail bases of substantially greater width, and also to rails having different base contours and those of which the base flanges vary in thickness.

The edges 16^a and 17^a of the jaw extremities 25 bite into the upper surface of the base flange 9^a, the edge 16^a being particularly effective in preventing creepage of the rail in the direction indicated by the arrow, Fig. 1, while the edge 17^a is particularly effective 30 in preventing creepage of the rail in the opposite direction. The device is applied to the rail from one side thereof directly along one side face of a tie, it being unnecessary for the device to be moved longitudinally 35 of the rail after being applied. The jaw extremities and the seats 13, as the device is applied to the rail, tend to bite into the rail base which is desirable, as it increases the hold of the device on the rail.

40 As will be readily appreciated, when the device is applied to a rail in the position shown in Fig. 3, the bottom portions of the jaws are spread apart from the normal position as indicated by dotted lines in said 45 Fig. 3. With the anchor in the position as shown by solid lines in Fig. 3, the jaw 15 serves as a resilient means tending to twist the jaw 14 in counter-clockwise direction. It is also evident that pressure upon the 50 outer face of the jaw 14 below the level of the rail also tends to twist the jaw 14 in counter-clockwise direction in said Fig. 3. It is thus plain that the means by which the 55 jaw 14 is held constantly by resilient force in gripping position tends to twist the jaw 14 in the same direction as that in which there is the tendency to twist the jaw by contact with the tie.

60 The grip of the device on the rail is thus seen to be two-fold. In the first place, there is the direct grip by reason of the spreading of the jaws from the bearings 13 in the application of the device to a rail. In the second place, there is the shackle hold or twisting grip effected by each jaw by reason of

the resilient action of the other jaw, such shackle hold or grip being strengthened by the pressure of the tie when there is a tendency for the rail to creep.

65 The device is of simple and compact construction and inexpensive to manufacture. It may be readily removed from the rail by prying down the connected ends of the portions 7 and 8 and then driving the device transversely from the rail base. After having been removed, it may be again applied to the rail.

I do not intend to limit my invention to the details of construction shown and described, except only in so far as certain of 80 the appended claims are specifically so limited, as it will be obvious that modifications may be made without departing from the principles of my invention.

85 I claim:

1. A device for preventing the longitudinal creep of railroad rails, comprising means extending transversely under the rail base and provided at one end with a seat adapted to engage the bottom of the rail base and with jaw means adapted to extend around and over the adjacent rail base flange, said jaw means terminating in two portions adapted to engage the upper side of said flange, one of said portions initially being relatively close to said seat so that it is forced away from said seat when the device is driven transversely onto the rail, and means at the other end of said first mentioned means adapted to engage the other base flange in such manner that reverse transverse movement of the device on the rail is prevented.

90 2. A device for preventing the longitudinal creep of railroad rails, comprising means extending transversely under the rail base and formed at one end with a seat adapted to engage the bottom of the rail base and with jaw means adapted to extend around and over the adjacent rail base flange, said 95 jaw means terminating in two portions which are adapted to engage the upper side of said flange and to be forced away from said seat when the device is driven transversely onto the rail, one of said portions being bent in the direction in which the rail tends to creep, and means at the other end of said first mentioned means adapted to engage the other base flange in such manner 100 that reverse transverse movement of the device on the rail is prevented.

105 3. A device for preventing the longitudinal creep of railroad rails, comprising means extending transversely under the rail base and provided at one end with a seat adapted to engage the bottom of the rail base and with jaw means adapted to extend around and over the adjacent rail base flange, said jaw means terminating in divergent bent portions 110 so arranged that they 115

100

- engage the upper side of said flange and are forced away from said seat when the device is driven transversely onto the rail, and means at the other end of said first mentioned means adapted to engage the other base flange in such manner that reverse movement of the device on the rail is prevented.
4. A device for preventing the longitudinal creep of railroad rails, comprising means extending transversely under the rail base and formed at one end with a seat adapted to engage the bottom of the rail base and with a pair of jaws adapted to 10 extend around and over the adjacent base flange, the extremities of said respective jaws extending longitudinally of the rail but in opposite directions and being so arranged that they engage the upper side of 15 said flange and are forced away from said seat when the device is driven transversely onto the rail, and means at the other end of said first mentioned means adapted to engage the other base flange in such manner that reverse transverse movement of the device on the rail is prevented.
5. A device for preventing the longitudinal creep of railroad rails, comprising means extending transversely under the rail 20 base and provided at one end with a seat adapted to engage the bottom of the rail base and with jaw means adapted to extend around and over the adjacent rail base flange, said jaw means terminating in two 25 portions adapted to engage the upper side of said flange, said portions initially being relatively close to said seat so that they are forced away from said seat when the device is driven transversely onto the rail, and 30 means at the other end of said first mentioned means adapted to engage the other base flange in such manner that reverse transverse movement of the device on the rail is prevented.
6. A device for preventing the longitudinal creep of railroad rails, comprising means extending transversely under the rail base and provided with a tie abutting means and at one end with jaw means adapted to 35 extend around and over one of the rail base flanges, said jaw means terminating in two portions adapted to engage the upper side of said flange when the device is driven transversely onto the rail, and means at the other end of said first mentioned means adapted to engage the other base flange in such manner that reverse transverse movement of the device on the rail is prevented.
7. A device for preventing the longitudinal creep of railroad rails, comprising means extending transversely under the rail base and provided with a tie abutting means and at one end with a seat adapted to engage the bottom of the rail base and with jaw means adapted to extend around and over one of the rail base flanges, said jaw means terminating in two portions adapted to engage the upper side of said flange when the device is driven transversely onto the rail, and means at the other end of said first mentioned means adapted to engage the other base flange in such manner that reverse movement of the device on the rail is prevented, one of said portions being bent in the direction in which the rail tends to creep, whereby the extremity of said last mentioned portion tends to bite increasingly into the flange under a creeping strain.
8. A one-piece device for preventing the longitudinal creep of railroad rails, comprising a metal bar bent substantially medially and having its two portions extending substantially transversely under the rail base, the free ends of said respective portions being bent to form jaws adapted to extend around and over one of the rail base flanges, said jaws having their respective extremities bent at substantially right angles thereto so that said extremities extend longitudinally of the rail but in opposite directions and engage the upper side of said flange when the device is driven transversely onto the rail, the connected ends of said portions being provided with a shoulder adapted to engage the other base flange in such manner that reverse transverse movement of the device on the rail is prevented, said portions being so formed that they are subjected to opposed twisting strains when the device is applied to the rail.
9. A one-piece device for preventing the longitudinal creep of railroad rails, comprising a metal bar bent substantially medially and having its two portions extending substantially transversely under the rail base, the free ends of said respective portions being bent to form jaws adapted to extend around and over one of the rail base flanges and to engage the upper side of said flange when the device is driven transversely onto the rail, the connected ends of said portions being provided with a shoulder adapted to engage the other base flange in such manner that reverse transverse movement of the device on the rail is prevented.
10. A one-piece device for preventing the longitudinal creep of railroad rails, comprising a metal bar bent substantially medially and having its two portions extending substantially transversely under the rail base, the free ends of said respective portions being bent to form seats adapted to engage the bottom of the rail base and then so as to form jaws adapted to extend around and

- over the adjacent rail base flange, said jaws being so arranged that they bear upon the upper side of said flange and are forced away from said seats when the device is driven transversely onto the rail, the connected ends of said portions being provided with a shoulder adapted to engage the other base flange in such manner that reverse transverse movement of the device on the rail is prevented.
11. A one-piece device for preventing the longitudinal creep of railroad rails, comprising a metal bar bent substantially medially and having its two portions extending substantially transversely under the rail base, the free ends of said respective portions being bent to form jaws adapted to extend around and over one of the rail base flanges and to engage the upper side of said flange when the device is driven transversely onto the rail, the extremity of one of said jaws being bent in the direction in which the rail tends to creep, the connected ends of said portions being provided with a shoulder adapted to engage the other base flange in such manner that reverse transverse movement of the device on the rail is prevented.
12. A one-piece device for preventing the longitudinal creep of railroad rails, comprising a metal bar bent substantially medially and having its two portions extending substantially transversely under the rail base, the free ends of said respective portions being bent to form seats adapted to engage the bottom of the rail base and then so as to form jaws adapted to extend around and over the adjacent rail base flange, said jaws being so arranged that they bear upon the upper side of said flange and are forced away from said seats when the device is driven transversely onto the rail, the extremity of one of said jaws being bent in the direction in which the rail tends to creep, the connected ends of said portions being provided with a shoulder adapted to engage the other base flange in such manner that reverse transverse movement of the device on the rail is prevented.
13. A one-piece device for preventing the longitudinal creep of railroad rails, comprising a metal bar bent substantially medially and having its two portions extending substantially transversely under the rail base, the free ends of said respective portions being bent to form jaws adapted to extend around and over one of the rail base flanges, the extremities of said respective jaws being bent divergently and adapted to engage the upper side of said flange when the device is driven transversely onto the rail, the connected ends of said portions being provided with a shoulder adapted to engage the other base flange in such manner that reverse transverse movement of the device on the rail is prevented.
14. A one-piece device for preventing the longitudinal creep of railroad rails, comprising a metal bar bent substantially medially and having its two portions extending substantially transversely under the rail base, the free ends of said respective portions being bent to form seats adapted to engage the bottom of the rail base and then so as to form jaws adapted to extend around and over the adjacent rail base flange, said jaws having their respective extremities bent divergently and being so arranged that they bear upon the upper side of said flange and are forced away from said seats when the device is driven transversely onto the rail, the connected ends of said portions being provided with a shoulder adapted to engage the other base flange in such manner that reverse transverse movement of the device on the rail is prevented.
15. A one-piece device for preventing the longitudinal creep of railroad rails, comprising a metal bar bent substantially medially and having its two portions extending substantially transversely under the rail base, the free ends of said respective portions being bent to form jaws adapted to extend around and over one of the rail base flanges, said jaws having their respective extremities bent at substantially right angles thereto so that said extremities extend longitudinally of the rail but in opposite directions and engage the upper side of said flange when the device is driven transversely onto the rail, the connected ends of said portions being provided with a shoulder adapted to engage the other base flange in such manner that reverse transverse movement of the device on the rail is prevented.
16. A one-piece device for preventing the longitudinal creep of railroad rails, comprising a metal bar bent substantially medially and having its two portions extending substantially transversely under the rail base, the free ends of said respective portions being bent to form seats adapted to engage the bottom of the rail base and then so as to form jaws adapted to extend around and over the adjacent rail base flange, said jaws having their respective extremities bent at substantially right angles thereto so that said extremities extend longitudinally of the rail but in opposite directions and so arranged that they bear upon the upper side of said flange and are forced away from said seats when the device is driven transversely onto the rail, the connected ends of said portions being provided with a shoulder adapted to engage the other base flange in such manner that reverse transverse movement of the device on the rail is prevented.
17. A rail anchor comprising a yoke having jaws on the arms both adapted to be driven laterally of the rail onto one of the

flanges thereof, and means for holding the anchor from backing transversely from the flange, the arrangement being such that the operation of applying the anchor to the rail 5 serves to twist the jaws in opposite directions about axes extending transversely of the rail.

18. A rail anchor comprising a yoke having jaws on the arms both adapted to be driven laterally of the rail onto one of the flanges thereof, and means for holding the anchor from backing transversely from the flange, the arrangement being such that the planes of the jaws normally converge and 10 that the operation of applying the anchor to the rail serves to twist the jaws in opposite directions towards parallelism.

19. A rail anchor comprising a yoke having jaws on the arms both adapted to be driven laterally of the rail onto one of the flanges thereof, and means for holding the anchor from backing transversely from the flange, the arrangement being such that the vertically extending portions of the jaws 25 normally stand in converging position and that the operation of applying the anchor to the rail serves to twist both jaws about axes extending transversely of the rail into substantially vertical position.

20. A rail anchor comprising a yoke having jaws on the arms both adapted to be driven laterally of the rail onto one of the flanges thereof with the yoke beneath the rail transversely thereof, and a lug on the 30 yoke adapted to engage the opposite flange for holding the anchor from backing transversely from the flange, the arrangement being such that the operation of applying the anchor to the rail serves to twist the jaws in opposite directions about axes extending transversely of the rail.

21. A rail anchor comprising a yoke having jaws on the arms both adapted to be driven laterally of the rail onto one of the flanges thereof, and means for holding the anchor from backing transversely from the flange, the arrangement being such that the operation of applying the anchor serves to distort the shape by spreading apart the bottom portions of the jaws whereby pressure on the outer face of either jaw below the level of the rail tends to twist such jaw in the same direction as that in which there is a tendency to twist the jaw by reason of the spring pressure due to the distortion of the anchor in its application to the rail.

22. A rail anchor comprising a yoke having jaws on the arms both adapted to be driven laterally of a rail onto one of the flanges thereof with the yoke extending entirely across the bottom face of the rail, and means on the yoke at the opposite end adapted to engage the adjacent flange for holding the anchor from backing transversely from the flange, said jaws comprising portions

extending longitudinally of the rail along the upper face of the flange at opposite faces of the anchor, the arrangement being such that the operation of applying the anchor serves to distort the shape by spreading 70 apart the bottom portions of the jaws whereby pressure on the outer face of either jaw below the level of the rail tends to twist such jaw in the same direction as that in which there is a tendency to twist the jaw by 75 reason of the spring pressure due to the distortion of the anchor in its application to the rail.

23. A rail anchor comprising a bearing adapted to engage the bottom face of a rail flange, a jaw connected with the bearing and disposed in position to be brought into engagement with the upper face of the flange, the distance between the jaw and the said bearing normally being such that the device 80 must be distorted by spreading the jaw and bearing apart for the application of the device in operative position on the rail, and resilient means normally exerting a constant pressure tending to twist the jaw and the 85 bearing about a transverse axis for giving them a shackle hold on the upper and bottom faces of the flange in addition to their grip by virtue of the vertical distortion of 90 the jaw.

24. A rail anchor comprising a bearing adapted to engage the bottom face of a rail flange, a jaw connected with the bearing and disposed in position to be brought into engagement with the upper face of the flange, the distance between the jaw and the said bearing normally being such that the device must be distorted by spreading the jaw and bearing apart for the application of the device in operative position on the rail, and the arrangement being such that upon the 100 application of the device to the rail the engagement of the jaw with the upper face of the flange tends to twist the end portion of the device comprising the jaw and the bearing about a transverse axis, and resilient means normally exerting a constant pressure tending to hold the jaw and bearing against 105 such twisting movement.

25. A rail anchor comprising a bearing adapted to engage the bottom face of a rail flange, a jaw connected with the bearing and disposed in position to be brought into engagement with the upper face of the flange and comprising a portion extending longitudinally of the rail substantially at right angles with respect to the body of the jaw, and resilient means normally exerting a constant pressure tending to twist the end portion of the device comprising the jaw and the bearing about a transverse axis in the direction for producing a pressure upon the flange by the free end of the longitudinally extending portion of the jaw.

26. A rail anchor comprising a bearing 130

- adapted to engage the bottom face of a rail flange, a jaw connected with the bearing and disposed in position to be brought into engagement with the upper face of the flange and comprising a portion extending longitudinally of the rail substantially at right angles with respect to the body of the jaw, the arrangement being such that upon the application of the device to the rail the engagement of the free end of the longitudinally extending portion of the jaw with the upper face of the flange tends to twist the end portion of the device comprising the jaw and the bearing about a transverse axis, and resilient means normally exerting a constant pressure tending to hold the jaw and bearing against such twisting movement.
27. A rail anchor comprising a bearing adapted to engage the bottom face of a rail flange, a jaw connected with the bearing and disposed in position to be brought into engagement with the upper face of the flange and comprising a portion extending longitudinally of the rail substantially at right angles with respect to the body of the jaw, said longitudinally extending portion being arranged normally to extend downwardly slightly towards its free end whereby upon the application of the device to the rail the engagement of the end of the longitudinally extending portion with the upper face of the flange tends to twist the end portion of the anchor comprising the jaw and bearing about a transverse axis, and resilient means normally exerting a constant pressure tending to hold the jaw and bearing against such twisting movement.
28. A rail anchor comprising a yoke having jaws on the arms both adapted to be driven laterally of a rail onto one of the flanges thereof, and means for holding the anchor from backing transversely from the flange, the arrangement being such that the operation of applying the anchor to the rail serves to distort the anchor by spreading the jaws upwardly with respect to the arms of the yoke and by twisting the jaws in opposite directions about axes extending transversely of the rail.
29. An anticreeper comprising a rolled bar bent to form at one end a tie abutting portion, an arm adapted to engage the upper portion of the rail base and a rail base edge engaging portion and at the other end thereof of a second arm and base edge engaging portion adapted respectively to engage and grip the upper surface and the edge of the rail base.
30. A one-piece rail anchor comprising a bar having one end bent over to form an arm adapted to engage the upper surface of the rail base and a tie engaging portion, the other end overturned to form a jaw adapted to embrace the rail base and grip the upper surface thereof, and an intermediate por-
- tion fashioned to provide a seat adapted to engage the edge of the rail base opposite said jaw and in spaced relation to the tie engaging portion.
31. An anticreeper, comprising a rolled bar, adapted to be transversely applied upon a rail base, having at one end an arm adapted to grip the top of the rail base and rail base edge engaging seat and, at the other end, an arm adapted to engage the top of the rail base, a tie engaging portion, adjacent said arm, and a seat adapted to engage the edge of the rail base to lock said anticreeper in position on the rail.
32. An anticreeper, comprising a rolled bar adapted to be applied transversely upon the rail base formed with a tie engaging portion, arms upon the two ends thereof adapted to grip the upper surface of the rail base, and a seat in spaced relation to said tie engaging portion adapted automatically to engage the rail base when said anticreeper is forced into position to lock the same in position.
33. A device for preventing the longitudinal creep of railroad rails comprising means extending substantially transversely under the rail base, a jaw on one end of said means and adapted to extend around and over one of the rail base flanges, said jaw and means being so formed in relation to each other that said means exerts an upward pressure against the bottom of the rail base and said jaw a downward pressure against the top of said flange when the device is applied to the rail, a shoulder on the other end of said means and adapted to engage the edge of the other rail base flange, and a tie abutting portion depending from said means at a point adjacent said shoulder.
34. A device for preventing the longitudinal creep of railroad rails comprising means extending substantially transversely under the rail base, a jaw on one end of said means and adapted to extend around and over one of the rail base flanges, said jaw and means being so formed in relation to each other that said means exerts an upward pressure against the bottom of the rail base and said jaw a downward pressure against the top of said flange when the device is applied to the rail, a shoulder on the other end of said means and adapted to engage the edge of the other rail base flange, and a foot piece depending from said means at a point adjacent said shoulder, the tie engaging face of said foot-piece being in a plane substantially forward of the adjacent vertical side of said means, with respect to the direction of creepage, for the purpose described.
35. A device for preventing the longitudinal creep of railroad rails, comprising means extending transversely under the rail base, means connected with one end of said

first named means and extending around and bearing on the upper face of one of the rail base flanges, and means connected with the other end of said first named means and bearing against the under face of said base flange.

36. A device for preventing the longitudinal creep of railroad rails, comprising means extending transversely under the rail base, a jaw connected with one end of said means and extending around and bearing on the upper face of one of the rail base flanges, and an arm yieldably connected with the other end of said means and bearing against the under face of said base flange.

37. A one-piece device for preventing the longitudinal creep of railroad rails, comprising a member extending transversely under the rail base, said member being formed at one end so as to provide a jaw extending around and bearing on the upper face of one of the rail base flanges, said member being formed at the other end so as to provide an arm having a portion bearing against the under face of said base flange.

38. A one-piece device for preventing the longitudinal creep of railroad rails com-

prising a substantially rigid bar of resilient metal extending transversely under the rail base, said bar being bent at one end to provide a jaw and at the other end to provide an arm, said jaw extending around and bearing on the upper face of one of the rail base flanges, said arm having a portion bearing against the under face of said base flange.

39. A one-piece device for preventing the longitudinal creep of railroad rails, comprising a metal bar formed so as to provide a jaw adapted to extend around and over one of the rail base flanges, a medial portion adapted to extend substantially transversely under the rail base, a shoulder adapted to engage the edge of the other rail base flange, and a downwardly extending tie abutting portion connected with the medial portion adjacent said shoulder, said jaw and medial portion being so formed in relation to each other that said medial portion exerts an upward pressure against the bottom of the rail base and said jaw a downward pressure against the top of the flange adjacent thereto when the device is applied to the rail.

ROLANDIS A. BLAIR.
